UNITED STATES PATENT OFFICE.

ROY CLEVELAND CREED, OF VIRGINIA, ILLINOIS.

PISTON-GROOVE TOOL.

Application filed August 1, 1922. Serial No. 578,925.

To all whom it may concern:

Be it known that I, Roy C. Creed, a citizen of the United States, and resident of Virginia, in the county of Cass and State of Illinois, have invented certain new and useful Improvements in Piston-Groove Tools, of which the following is a specification.

My invention relates to improvements in piston groove tools and it consists in the combinations, constructions and arrangements herein described and claimed.

An object of my invention is to provide a tool of the character described which is extremely simple in construction and which affords facilities whereby the grooves of pistons of internal combustion engines may be quickly and conveniently cleaned or enlarged, as by deepening, widening or chamfering an edge of the groove, with the necessity of completely removing the piston from a machine in which provided and putting the piston in a lathe obviated.

A further object of my invention is to provide a tool of the character described which is adapted for adjustment to permit of use in connection with the cleaning or enlarging of the grooves of pistons of various sizes.

A still further object of my invention is to provide a tool of the character described which is manually operable to perform the functions for which provided, and which is thoroughly practical commercially.

Other objects and advantages will be apparent from the following description, and the novel features of the invention will be particularly outlined in the appended claims.

My invention is illustrated in the accompanying drawings, forming a part of this application, in which—

Figure 1 is a view showing the tool embodied in the invention in position in a groove of a piston, the piston being shown in section,

Figure 2 is a relatively enlarged view taken at right angles to Figure 1, the tool being shown in section and the piston in side elevation, and

Figure 3 is a perspective view of the tool detached.

A tool embodying the invention in the form in which illustrated in the drawings comprises a carrying frame designated generally at 1. The carrying frame 1 is substantially U-shaped and includes a pair of parallel arm portions 2, 3 having right an-

gular web sections 4, 5 respectively at their similar ends, the web sections 4, 5 being of less thickness than the arms 2, 3 and being adapted to be adjustably and pivotally connected together so that the lowermost side of the web portion 4 will lie in the plane of the lower side of the arm 3 and the uppermost side or face of the web portion 5 will lie in the plane of the upper side of the arm 2. The upper and lower faces or sides of each arm of the frame are thus disposed in the planes of the corresponding sides of the other arm. In the present instance, the web section 4 is provided with a longitudinal series of threaded openings 6 therethrough adapted to be threadedly engaged by a shouldered pin 7 which is provided with screw threads adjacent to its extremity and is adapted to be projected through an opening 8 in the web section 5 until the shoulder of the pin rests upon the face of the web section 5. It will be apparent that the arms 2 and 3 may be spaced at various distances apart by placing the opening 8 of the web portion 5 selectively in alignment with the threaded openings 6 through the web section 4.

The arms 2, 3 are provided at their ends remote from the web sections with parallel inwardly offset extensions 9 and 10 respectively, which extensions preferably have the remote sides thereof rounded so as to be adapted to be gripped in the hand. The extensions 9 and 10 constitute handle or grip portions which may be conveniently gripped to effect manipulation of the carrying frame 1 as will presently appear.

The arms 2, 3 are provided with aligned slots 11, 12 respectively therethrough. The slot 11 is adapted to receive the intermediate portion 13 of a tool holding and guide block 14. The latter consists of the intermediate portion 13, a portion 15 of less thickness than the intermediate portion and extending laterally of the inner side of the arm 2 and a portion 16 of greater thickness than the intermediate portion 13 and being merged into the latter by shoulders 17 which abut the outer side of the arm 2 along the upper and lower edges of the slot 11.

The inner portion 15 of the block is formed with a V-shaped portion cutaway as indicated at 18 and is of a thickness to enter and slidably engage a groove 19 in a piston 20. The block 14 is releasably locked to the arm 2 through the agency of shouldered pins

or screws 21 extending through aligned openings in the block and in the spaced apart portions of the arm 2 defined by the slot 11. The screws or pins 21 are in 5 threaded engagement adjacent to their extremities with the walls of the openings through the lower portion of the arm 2, as indicated at 22.

The block 14 is provided with an integral 10 extension 23 extending laterally of the relatively thick portion 15 thereof and being merged into the latter at a point intermediate the side edges of the block whereby a line extending axially of the extension 23 15 will, if extended, bisect the angle defined at the juncture of the sides of the cut-away portion 18. A bore 24 which is non-circular in cross sectional contour extends through the block 14 from the apex of the V-shaped 20 cut-away portion into the extension 23, being merged midway of the length of the extension into a counter-bore 25 which is of circular cross sectional contour and extends the remainder of the length of the extension. 25 The bore 24 is adapted to receive the shank of a cutting tool, such as indicated at 26 and the walls of the bore 24 are cut-away at one side at the juncture of the latter with the cut-away portion 18 to define 30 a space 27 at one side of the cutting tool 26 adjacent to the cutting edge of the latter. The cutting tool 26 may be adjusted laterally and releasably held in laterally adjusted position within the bore 24 by means 35 of a clamping screw 28 extending in threaded engagement with a radial opening in the upper part of the extension 23 into the bore 24 and a pair of spaced apart clamping screws 29 extending in threaded 40 engagement with radial openings through the lower part of the extension 23 into the bore 24. The cutting tool 26 may be adjusted longitudinally of the bore 24 toward the groove 19 by means of an adjusting 45 screw 30 which is in threaded engagement with the counter-bore 25. Moreover, the cutting tool 26 may be held in longitudinally adjusted position between the bottom or inner wall of the groove 19 and the inner 50 end of the adjusting screw 30 so that a very slight axial or longitudinal movement of the cutting tool may be yieldingly permitted, this being due to the provision of a longitudinal slit 31 extending in the screw 30 55 from the inner end of the latter. The cutting tool 26 is thus placed under tension, tending to hold it in engagement with the groove 19.

The groove 12 is adapted to receive the 60 relatively thick portion 32 of a guide block 33 so that spaces are provided between the side walls of the groove and the side walls of the block 33 as indicated at 34—34 in Figure 3 of the drawings. The block 33 includes in addition to the portion 32 a por-

tion 35 of reduced thickness which extends beyond the inner wall of the arm 3 in confronting relation to the portion 15 of the block 14. The portion 35 has a V-shaped portion 36 and is of a thickness to enter and 70 slidingly engage the groove 19 at points diametrically opposite the points at which the bottom wall of the groove 19 is contacted by the portion 15 of the block 14. The block 33 is held in association with the arm 3 by a 75 shouldered pin or screw 37 extending through aligned openings in the portion of the arm 3 defined by the slot 12 and the portion 32 of the block 33, the pin or screw 37 being in threaded engagement adjacent to its extremity with the walls of the opening through the lowermost portion of the arm 3 as indicated at 38.

From the foregoing description of the various parts of the device, the operation 80 thereof may be readily understood. The sections of the frame 1 which have been described are connected together through the agency of the screw or pin 7 and in the manner described to adapt the device for use 85 with a piston of a given size. A cutting or scraping tool is then inserted in the bore 24 and adjusted longitudinally and laterally, and then locked to the block 14 in adjusted position. The handle portions 9 and 10 are 90 then gripped in the hands so that the co-operating inner end portions or jaws 15 and 35 of the blocks 14 and 33 respectively are held in engagement or contact with the walls 95 of the groove, the cutting or scraping portion of the tool being thus maintained in operative engagement with one or more of the walls of the groove. The device as a 100 whole is then rotated about the axis of the piston, the cutting tool being guided during 105 such rotation by the jaws 15 and 35 of the blocks engaging the piston groove. Since spaces are provided between the sides of the block 33 and the side walls of the slot 12, limited rotary or swiveling movement of 110 the block about the axis of the groove is permitted as the device as a whole is rotated about the axis of the piston, whereby rotary movement of the device about the axis of the piston and in operative engagement with 115 the groove of the piston is facilitated.

Cutting tools 26 having cutting edges adapted for use in accomplishing various operations, as for instance to deepen or widen a piston groove or to chamfer an edge 120 of the piston groove may be used selectively in the tool, as will be obvious from the foregoing.

Obviously, my invention is susceptible of 125 embodiment in forms other than that disclosed in the accompanying drawings, and I therefore consider as my own all modifications of the form of the device herein disclosed, which fairly fall within the scope of the appended claims.

I claim:—

1. A device of the character described comprising a substantially U-shaped frame consisting of a pair of connected together sections and including a pair of substantially parallel arms adapted to straddle a piston, said arms having aligned slots therethrough, a tool holding guide block secured to one of said arms with a portion of the block extending through the slot in the arm into a piston ring groove of the piston, a cooperating guide block secured to the other arm of the frame with a portion of the block extending through the slot of the second arm into the said piston ring groove.
2. A device of the character described comprising a substantially U-shaped frame consisting of a pair of adjustably connected together sections and including a pair of substantially parallel arms adapted to straddle a piston, said arms having aligned slots therethrough, a tool holding guide block secured to one of said arms with a portion of the block extending through the slot in the arm into a piston ring groove of the piston, and a cooperating guide block secured to the other arm of the frame with a portion of the block extending through the slot of the second arm into the said piston ring groove.
3. A device of the character described comprising a substantially U-shaped frame consisting of a pair of adjustably connected together sections and including a pair of substantially parallel arms adapted to straddle a piston, said arms having aligned slots therethrough, a tool holding guide block secured to one of said arms with a portion of the block extending through the slot in the arm into a piston ring groove of the piston, and a cooperating guide block secured to the other arm of the frame with a portion of the block extending through the slot of the second arm into the said piston ring groove, said first named block having a bore therethrough adapted to receive the shank of a tool so that the work engaging portion of the latter will extend into engagement with the piston groove.
4. A device of the character described comprising a substantially U-shaped frame
5. A device of the character described comprising a frame consisting of arm portions having right angular web sections at their similar ends and inwardly offset handle portions merged into the arms at the other ends of the latter, means pivotally connecting the web sections of the frame in lapped relation to space the arms apart as desired, and means carried by the arms for adjustably supporting a cutting or scraping tool in engagement with a piston ring groove and for guiding the tool along the groove.
6. A device of the character described comprising a frame consisting of arm portions having right angular web sections at their similar ends and inwardly offset handle portions merged into the arms at the other ends of the latter, means pivotally connecting the web sections of the frame in lapped relation to space the arms apart as desired, and means carried by the arms for adjustably supporting a cutting or scraping tool in engagement with a piston ring groove and for guiding the tool along the groove, said means including a pair of blocks detachably secured to the arms in confronting relation in respect to each other, one of said blocks being adapted to hold a cutting or scraping tool and the other of said blocks being pivotally attached to one of said arms, said blocks having portions adapted to enter the piston ring groove and to engage with the latter at diametrically opposite points.

ROY CLEVELAND CREED.
